ILLUMINATED DISPLAY ASSEMBLY
Merrill Krakauer and Walter L. Koch, Livingston, N.J.,
assignors to Rowe Manufacturing Co., Inc., Whippany,
N.J., a corporation of New York

Filed Aug. 7, 1959, Ser. No. 832,232

3 Claims. (Cl. 40—126)

Our invention relates to an illuminated display assembly and more particularly to a merchandising machine display assembly which closely simulates the appearance of an article which is dispensed by the machine.

In the merchandising machine art, it is necessary to apprise the customer of the kind and brands of merchandise which are to be sold by the machine. One manner in which this purpose can be accomplished is to print or otherwise impress a legend containing this information on the machine. It will be appreciated that this method of merchandising the articles to be sold accomplishes nothing in the way of promoting sales as by prompting "impulse buying" since such a legend performs no function other than that of merely informing a potential customer of the merchandise which is available.

If a merchandising machine is to act as an effective "salesman" in a highly competitive market such as the cigarette market, it is necessary that the machine be provided with an attractive display to induce potential customers to buy. It has been suggested that a dummy display which simulates the appearance of an article dispensed by the machine be mounted on the machine. It will be appreciated that such a display must have the shape of the article such as a package of cigarettes and it must carry indicia simulating those printed on the article package.

One method which has been proposed in the prior art for making such a display is to first print a plastic sheet with the indicia simulating that on the article package and then to mold the sheet to the shape of the article. As a result of the molding operation, the indicia placed on the sheet before molding are distorted with the result that the display does not closely simulate the appearance of the article being sold. These molded displays of the prior art, moreover, become dusty and the indicia becomes worn and dull after a period of time in use of the display. When the indicia becomes dull and lifeless as a result of soiling and wear, the entire display must be replaced with the resultant expense to the operator.

We have invented an illuminated display assembly for a merchandising machine which overcomes the defects of displays of the prior art. Our display assembly very closely simulates the appearance of an article dispensed by the merchandising machine since it introduces no distortion of the indicia simulating that of an actual article being dispensed by the machine. One form of our display protects the indicia of the display against wear and deterioration even after a long period of time in use. Another form of our display permits the particular brand or type of article being simulated to be changed without discarding the entire old display and thus the particular type or kind of article being simulated may be changed with much less expense than is involved in changing the display in the prior art. Our display assembly is simple and inexpensive in construction.

One object of our invention is to provide an illuminated display assembly which very closely simulates the appearance of an article being sold by a merchandising machine without distortion of the indicia simulating that of the article.

Another object of our invention is to provide an illuminated display assembly in which the indicia of the display is protected against soiling and wear in use.

Still another object of our invention is to provide an

2

illuminated display assembly which permits the particular type or brand of article being simulated to be changed in a rapid, expeditious and inexpensive manner.

A further object of our invention is to provide an illuminated display assembly which is simple and inexpensive in construction.

Other and further objects of our invention will appear from the following description:

In general our invention contemplates the provision of an illuminated display assembly for a merchandising machine including a transparent housing formed to the shape of the article being simulated together with a translucent insert for the housing. We fold the insert to the shape of the article from a flat blank printed with indicia simulating that carried by the actual article. We provide our assembly with a frame carrying the housing and insert. In one form of our invention the frame is formed with a backing member and the insert is sealed between the housing and the frame backing to protect the insert carrying the indicia. In another form of our invention the insert carrying the indicia is readily removable from the housing to permit it to be replaced in a rapid, expeditious, and inexpensive manner. A lamp disposed within the housing illuminates the display by transmitted light passing through the insert. We employ any suitable means for mounting the frame on a merchandising machine cabinet.

In the accompanying drawings which form part of the instant specification and which are to be read in conjunction therewith and in which like reference numerals are used to indicate like parts in the various views:

FIGURE 1 is an exploded view of one form of our illuminated display assembly showing the relation of the parts.

FIGURE 2 is a sectional view of the form of our illuminated display assembly shown in FIGURE 1.

FIGURE 3 is a plan view of a blank forming the insert of our illuminated display assembly.

FIGURE 4 is an exploded view showing the relationship of the various parts of an alternate form of our illuminated display assembly.

FIGURE 5 is a fragmentary elevation of a merchandising machine cabinet provided with the form of our illuminated display assembly shown in FIGURE 4.

FIGURE 6 is a sectional view of our illuminated display assembly taken along the line 6—6 of FIGURE 5.

FIGURE 7 is a perspective view of an alternate form of insert with a part broken away for the form of our illuminated display shown in FIGURE 4.

Referring now more particularly to FIGURES 1 and 2 of the drawings, our illuminated display assembly indicated generally by the reference character 10 includes a frame 12, the central portion of which carries a backing 14 in the shape of the article such as a package of cigarettes to be simulated. The frame 12 carries a peripheral flange 16 which assists in mounting the assembly on a merchandising machine cabinet in a manner to be described hereinafter. Preferably we mold the frame 12, the back 14 and the flange 16 as an integral unit from a suitable plastic material such for example as polystyrene, which, as will be explained hereinafter, may be either transparent or translucent.

Our assembly includes a cover indicated generally by the reference character 18 including a housing 20 in the form of the article, such as a package of cigarettes, to be simulated and a frame 22 provided with a peripheral flange 24. We mold the cover 18 from a suitable transparent material such for example as a clear polystyrene plastic, acrylic resins, allyl resins or the like. We so form the cover 18 with respect to the frame 12 and back 14 that frame 22 is adapted to fit closely over the frame 12, and backing 14 is adapted to fit within the housing 20.

We provide our assembly with an insert indicated generally by the reference character 26 carrying indicia such as the brand name and the like simulating the indicia provided on the package of the actual article dispensed by the machine. As can be seen by reference to FIGURE 3, we form the insert 26 from a flat blank 28 of material cut from a sheet to provide respective top and bottom extensions 30 and 32 and side extensions 34 and 36. In our assembly either the backing 14 or the insert 26 must be formed from translucent material. If desired, both the backing 14 and the insert 26 may be formed of translucent material. Preferably we form the insert 26 from a suitable translucent plastic such for example as polyethylene. While the blank 28 is in its flat state we print or otherwise impress on the blank indicia simulating that provided on the front, top, bottom, and sides of the article being simulated. We fold the top 30 and the bottom 32 along respective lines 38 and 40 and we fold the sides 34 and 36 along lines 42 and 44 to cause the insert 26 to assume the shape of the article being simulated.

If desired, we provide our assembly with a decorative mat 46 adapted to be sandwiched between the frame 22 and the frame 12 when the parts are assembled. We provide the mat 46 with a central opening 48 of substantially the same size as the front of the insert 26. When the parts of the form of our assembly shown in FIGURES 1 to 3 are assembled as shown in FIGURE 2, mat 46 is sandwiched between the frames 22 and 12 and the insert 26 is sandwiched between the housing 20 and the backing 14. We seal the insert 26 between the housing 20 and the backing 14 in any suitable manner such as by heat sealing the plastic members to each other or by applying an appropriate adhesive in the area of the flanges 16 and 24. In this manner no dust or dirt can collect on the insert carrying the indicia and the indicia is protected against deteriorating under the action of any external influence.

Referring now to FIGURE 4 an alternate form of our invention comprises the cover indicated generally by the reference character 18 having the housing 20, frame 22, and flange 24. In this form of our invention rather than having a backing 14 in the shape of the article being simulated, the frame 12 carries a central support plate 50. Any suitable means such for example as rivets 52 secure a plate 54 carrying a bracket 56 to the plate 50. We employ any suitable means such for example as a screw 58 to secure a lamp socket 60 to the bracket 56. Respective conductors 60 and 62 connected to a suitable source (not shown) of electrical energy light a lamp 64 in socket 60.

The form of our invention shown in FIGURE 4 also includes a mat 46 and an insert 26. In this form of our invention, we cut the blank 28 from a relatively heavy gauge sheet of plastic so that the insert has sufficient structural strength to retain its shape when disposed in housing 20 without the necessity of employing a backing such as the backing 14. This form of our invention permits the ready removal and replacement of the insert 26 without the necessity for replacing an entire display as is required in assemblies of the prior art.

Referring now to FIGURES 5 and 6, we have shown the form of our invention illustrated in FIGURE 4 in position on the door 66 of a merchandising machine cabinet. We dispose the assembly of the cover 18 having the frame 22 with the frame 12 in an opening 68 in the door 66 and with the flange 24 in engagement with the inside of the door. We employ any suitable means such for example as screws 70 for securing a retainer 72 to the inside of the door 66. Retainer 72 engages the flange 16 to hold the assembly in position on the door. We provide the form of our assembly shown in FIGURE 4 with openings 74 in the plates 54 and 50 to permit air to circulate within the housing 20. It will be understood that the form of our invention shown in FIGURES 1 and 2 may be assembled on a merchandising machine cabinet door in the same manner. Preferably we recess the cen-

tral portions of the frame 12 and 22 to enhance the appearance of the assembly. While we have described one specific means by which our assembly may be secured to the cabinet door 66, it is to be understood that any other appropriate means may be employed.

In a further form of our invention shown in FIGURE 7 in which the insert 26 is to be used with the form of our invention shown in FIGURE 4 is readily replaceable, we form the insert 26 from a relatively thin blank 28 of plastic material and provide a separate removable plastic backing 76 molded to the shape of the article to be simulated and adapted to fit into the housing 20 to sandwich the blank 28 between the backing 76 and the housing 20. It will be appreciated that in this form of our invention one or the other of the backing 76 and the blank 28 must be formed of translucent material and if desired, both members may be formed from translucent material.

In use of the form of our invention shown in FIGURES 1 and 2, we assemble the cover 18 on the backing 14 with the insert 26 sandwiched between the housing 20 and the backing 14. The mat 46 is sandwiched between the frames 22 and 12. When the parts have been assembled, we seal the flanges 16 and 24 by any suitable means such for example as by the use of a suitable plastic adhesive. Our assembly may then be mounted on the door 66 of a merchandising machine in any convenient manner such as that described in connection with the form of our invention shown in FIGURE 4. A source of illumination such as the lamp 64 in this form of our invention is carried by the machine cabinet in a position to illuminate the insert 26 by light transmitted through the backing 14 and through the insert 26. This form of our invention seals the insert between the housing 20 and the backing 14 to protect the indicia against deterioration and dirt.

In the form of our invention shown in FIGURE 4, we assemble frame 22 on frame 12 with the insert 26 disposed within the housing. When it is desired to change the indicia, the parts may be separated and the insert 26 may readily be changed. If the insert 26 is formed from a blank 28 of relatively thin material, we provide the assembly with a separate backing 76.

It will be seen that we have accomplished the objects of our invention. We have provided an illuminated display assembly for a merchandising machine which very closely simulates the appearance of an article being dispensed without introducing distortion of the indicia such as is present in displays of the prior art. In one form of our invention, the insert carrying the indicia is sealed in an enclosed space to protect it against dirt and deterioration. In another form of our invention the insert carrying the indicia may be removed and replaced in the event that it becomes soiled or worn without the necessity for replacing the entire display. Our assembly is simple and inexpensive to construct.

It will be understood that certain features and subcombinations are of utility and may be employed without reference to other features and subcombinations. This is contemplated by and is within the scope of our claims. It is further obvious that various changes may be made in details within the scope of our claims without departing from the spirit of our invention. It is, therefore, to be understood that our invention is not to be limited to the specific details shown and described.

Having thus described our invention, what we claim is:

1. A merchandising machine display assembly for simulating the appearance of a boxlike package carrying indicia on a face and sides including in combination a base, a transparent housing conforming to the shape of said boxlike package carried by said base, said housing having an outwardly directed face and inwardly extending sides approximating the dimensions of the corresponding parts of said package, said housing being formed with an open back, a blank of translucent material cut to provide panels corresponding to the face and sides of said package, said panels carrying indicia simulating the indicia carried by the corresponding parts of said package, said blank being

folded to form an insert, said insert being nested within said housing through said open back with the side panels thereof in engagement with the sides of said housing.

2. A merchandising machine display assembly for simulating the appearance of a boxlike package bearing indicia on a face and sides including in combination a base forming a first frame, a transparent housing conforming to the shape of said boxlike package carried by said base, said housing having an outwardly directed face and inwardly extending sides approximating the dimensions of the corresponding parts of said package, said housing being formed with an open back, a blank of translucent material cut to provide panels corresponding to the face and sides of said package, said panels carrying indicia simulating the indicia carried by the corresponding parts of said package, said blank being folded to form an insert, said insert being nested in said housing through said open back with the side panels thereof in engagement with the sides of said housing, a second frame, a source of illumination carried by said second frame and means for holding said first and second frames together with said source of illumination disposed behind said insert.

3. A merchandising machine display assembly for simulating the appearance of a boxlike package bearing indicia on a face and sides including in combination a base forming a first frame, a transparent housing conforming to the shape of said boxlike package carried by said base, said housing having an outwardly directed face and inwardly extending sides approximating the dimensions of the corresponding parts of said package, said housing being formed with an open back, a blank of translucent

material cut to provide panels corresponding to the face and sides of said package, said panels carrying indicia simulating the indicia carried by the corresponding parts of said package, said blank being folded to form an insert, said insert being nested in said housing through said open back with the side panels thereof in engagement with the sides of said housing, a second frame, a source of illumination carried by said second frame, means for holding said first and second frames together with said source of illumination disposed behind said insert and a decorative mat sandwiched between said frames.
